UNITED STATES PATENT OFFICE.

EDWARD H. BRUNE, OF ST. LOUIS, MISSOURI.

MAGNETIC SEPARATOR.

Application filed July 21, 1924. Serial No. 727,187.

To all whom it may concern:

Be it known that I, EDWARD H. BRUNE, a citizen of the United States, residing at St. Louis, in the State of Missouri, have invented certain new and useful Improvements in Magnetic Separators, of which the following is a specification.

The present invention relates to magnetic separators and has for one of its objects 10 the provision of magnetic mechanism for removing metallic bodies, susceptible to the influence of magnetism, from garbage, refuse of all kinds, grain, etc.

Other objects of the invention are to provide a magnetic separator operable in proximity to a moving line of garbage, or other refuse, for picking out all bodies, elements or particles which are susceptible to the influence of a magnet; to provide a cone 20 shape interceptor so disposed to the line of travel of the garbage or other refuse that the larger bodies will be first picked up while the remainder are gradually intercepted according to their sizes until the 25 garbage, or other refuse, is ultimately free of all bodies, elements or particles susceptible to the influence of magnetism; and to provide an interceptor which ultimately spreads the garbage or other refuse to positively delete bodies or elements, as described above, therefrom, suitable means being provided to constantly relieve the interceptor from the adhering bodies, or objects.

Other objects of this invention will be apparent from the following description of the present preferred form of the invention taken in connection with the accompanying drawings wherein:—

Fig. 1 is a side elevational view of a magnetic interceptor constructed in accordance with this invention illustrating its application;

Fig. 2 is a fragmentary top plan view of the interceptor illustrating its application; and

Fig. 3 is an end elevational view of the same.

In the drawings, a base supporting structure 4 is shown which may be made of metal and of any desired configuration and is equipped with a superstructure generally designated 5 which supports a plurality of rollers 6 upon which a belt 7 is movably mounted. The belt in the present instance is shown to be of the endless type and is

trained around one or more pulleys mounted upon the supporting structure 4. By disposing the rollers 6 at an inclination the marginal edges of the belt 7 are flexed upwardly to prevent displacement of the garbage, or other refuse, over the margins of the belt. It is to be understood that the base supporting structure 4, superstructure 5, rollers 6, belt 7 and pulleys 8 are all well known in the art and are shown herein merely to illustrate the application of the invention. The belt is adapted to receive garbage or other refuse, grain or like materials, and moves in the direction indicated by the arrow in Fig. 1. It is desirable to relieve garbage of all metallic elements or substances if possible since, as is now well known, garbage is universally used as a hog food and is frequently treated by various processes for deleting certain food constituents therefrom for poultry and cattle food. It has been found from experiment that glass is uninjurious to hogs and hence does not of necessity have to be removed from the garbage, but metallic substances cannot, of course, be masticated and are manifestly undesirable. In addition to this literally tons of metallic elements, such as knives, forks, spoons and silver of all kinds are annually found in garbage throughout the United States and the salvage value of these elements is enormous. In addition to this the salvage value even of tin cans and like receptacles and elements is of very great value. Furthermore, in order to prevent damage to machinery used in the treatment of grain the latter must be relieved of extraneous metallic bodies. It is consequently the purport of the present invention to employ mechanism which may be utilized for all the purposes above recited.

The magnetic separator per se consists of a conically shaped drum 9 made of a suitable material such as brass, lead, rubber composition or wood and is rotatably mounted on supporting standards 10. The standards 10 are carried by the superstructure 5 as illustrated to advantage in Fig. 3. Fixedly mounted within the drum 9 is a magnetic segment 11 which may be fed by a motor or other suitable means which will keep the segment constantly magnetized. The segment 11 is conical shape in elevation so as to conform to the contour of the drum 9 and is of substantially the same length as the latter so that the drum 9 will be mag-

netized by the segment 11. The area or field of magnetic influence covered by the drum 9 will correspond substantially to the portion thereof which lies in proximity to the periphery of the segment, leaving a part of the drum which is not energized. Upon reference to Fig. 1 of the drawings it will be noted that the drum 9 is positioned immediately above the belt 7 and has its longitudinal axis arranged to lie parallel with the longitudinal axis of the belt. The small end of the cone is arranged to lie in the direction of movement of the upper run of the belt so that relatively large objects susceptible to magnetic influence will be first intercepted and caused to adhere to the periphery of the drum 9. In graded sequence other objects susceptible to magnetism will be picked up by the drum until ultimately the large end of the drum comes into such close proximity to the belt as to positively intercept very small particles or bodies susceptible to magnetic influence. In addition to this, the large end of the drum acts as a spreader so as to scatter the garbage, refuse, or other materials carried on the belt thereby eliminating the possibility of some metallic particles from being embedded beneath garbage or other materials not susceptible to magnetic influence and being carried off with the same.

In order to relieve the drum 9 from adhering objects, a scraper 12 is provided which may be carried by a pair of the standards 10 at one side of the drum preferably at a point where the drum is feebly magnetic, as shown in Fig. 3. The scraper may be of any desired construction but preferably impinges against the drum to disengage objects from the latter. By preference, the scraper is relatively wide to serve as a deflector for deflecting the objects away from the drum after they have been removed from the latter.

It is to be understood that the drum 9 and correspondingly the magnetic segment 11 may be of any desired size, but by preference the diameter of the large end of the drum appreciably protrudes beyond the margins of the belt 7 to positively traverse the complete lateral extent of the belt and eliminate the possibility of bodies or particles, especially those which are feebly magnetic, from passing on the belt unapprehended by the drum. Moreover the drum 9 may be rotated in any desired manner and through the instrumentality of any desired

mechanism. The general shape and manner of positioning the drum and magnetic segment is important. Numerous changes will suggest themselves to those skilled in the art to which this invention appertains within the scope of the claims hereto appended.

What is claimed is:-

1. In combination with a movable belt for conveying garbage, refuse, etc., a cone shape interceptor mounted above said belt and having its longitudinal axis arranged to lie parallel to the longitudinal axis of said belt for removing various sized bodies of predetermined characteristics from said garbage.

2. In combination with a movable belt for carrying garbage, refuse, etc., a magnetized drum rotatably mounted above said belt to intercept metallic objects carried by the latter, said drum being cone shaped and having its longitudinal axis arranged to lie parallel with the longitudinal axis of the belt for intercepting metallic bodies in sequence according to their sizes.

3. In combination with a movable belt for conveying garbage, refuse, etc., a cone shape metallic drum revolvably mounted above said belt having its longitudinal axis arranged to lie parallel with the longitudinal axis of the latter, a magnetized segment fixedly mounted within said drum to energize a predetermined portion of the latter, and a scraper impinging against said drum at a point free from the direct influence of said segment.

4. In combination with a movable belt for conveying garbage, refuse, etc., a cone shape magnetized drum arranged above said belt having the small end thereof appreciably spaced from the belt and the large end arranged in close proximity to the latter substantially as described.

5. In combination with a movable belt for conveying garbage, refuse, etc., a cone shaped magnetized drum rotatably mounted above said belt having its smaller end arranged to lie in the direction of movement of said garbage, refuse, etc., the surface of the drum lying at an angle to the plane of the conveyor.

6. In combination with a movable belt, a magnetized drum rotatably mounted above said belt the axis of which extends lengthwise of the belt, one portion of the periphery of said drum being disposed to lie in close proximity to the belt and another portion of the periphery of the drum being disposed to lie at a point remote from the belt.

In testimony whereof I affix my seal.
EDWARD H. BRUNE.
